UNITED STATES PATENT OFFICE.

FREDERIC A. DELANO, OF CHICAGO, ILLINOIS.

RAILWAY-TIE PLATE.

No. 835,602.

Specification of Letters Patent.

Patented Nov. 13, 1906.

Application filed April 24, 1905. Serial No. 257,201.

To all whom it may concern:

Be it known that I, FREDERIC A. DELANO, a citizen of the United States, residing at Chicago, in the county of Cook and State of Illinois, have invented certain new and useful Improvements in Railway-Tie Plates, of which the following is a specification.

This invention relates to that class of tie-plates which are placed under the ordinary railway-rail between its base and the upper surface of the railroad-tie to assist in resisting the ordinary wear in and cutting of the upper portion of such tie.

The principal object of the invention is to provide a simple, economical, and efficient two-piece tie-plate which will permit of the use of the most economical form of rail and at the same time minimize, if not entirely prevent, the ordinary injurious effects arising therefrom.

Other and further objects of the invention will appear from an examination of the drawings and the following description and claims.

The invention consists principally in a tie plate or plates for railway-rails composed of a plurality of pieces having base-embracing lugs on their opposed free edges and lever-like extensions extending outwardly and oppositely therefrom for fastening the tie-plate in position at points remote from the base-receiving portion thereof.

The invention consists, further and finally, in the features, combinations, and details of construction hereinafter described and claimed.

In the accompanying drawings, Figure 1 is a sectional elevation of a railway-rail and the parts of a tie-plate as such parts appear when constructed in accordance with these improvements, taken on line 1 of Fig. 2; Fig. 2, a plan view of the same; Fig. 3, a cross-sectional view of a railway-track formed of two rails as it appears when fitted with these improvements, and Fig. 4 a plan view of the same.

In the art to which this invention relates it is well known that there are many objections to the use of the ordinary tie-plates—that is, the tie-plates now in use—in that, first, the spikes or lag-screws enter the tie or sleeper at the points where it is subjected to the greatest strains and where the tie is liable to become broken, and hence such securing means are apt to become loose and permit the rapid destruction of the tie. Further, in the use of the ordinary T-rail the base is

made as wide as the height of the rail, which is not the most economical disposition of the metal. My improvements are designed to overcome these objections by providing a tie-plate formed in two pieces which will provide for the fastening means at a point or points remote from the rail-base. There are other advantages derived from the use of this construction, some of which are as follows: First, the spikes or lag-screws instead of entering the sleeper at the point of greatest stress or wear enter the railway-tie at a point, relatively speaking, remote therefrom—say several inches away—where the strains are much less; second, the structure permits the rail to have its ordinary wave motion in advance of the train, so that it may rise above the tie and eliminate the usual “pumping” action thereof. Further, it permits of the use of an economical rail in that the rail need not be more than four inches wide at the base and seven inches high, which while it weighs no more per yard than the old form of rail will be much stronger in resisting vertical strains. Finally, my improved tie-plate minimizes all cutting of the tie or the overturning of the rail, all of which will be thoroughly understood and appreciated by those skilled in the art.

In constructing a tie-plate in accordance with these improvements and using them in connection with a T-rail *a* I prefer to make it in two parts, one part *b* having bifurcations *b'* and *b''*, each in turn provided with rail-base-embracing lugs *c* at the opposed free ends or edges thereof. These rail-embracing lugs are arranged at the free ends of the bifurcated portion and extend upwardly and inwardly over the rail-base, as shown clearly in Figs. 1 and 2. Oppositely disposed, and preferably on the bifurcated portions, are what I prefer to term “base stop-lugs” *d*, which do not extend inwardly to embrace the rail. This portion of the plate is also provided with a perforated lever-like extending portion *e*, perforated, as shown, at a point, relatively speaking, remote from the rail-base—say several inches away—and through which any ordinary spike or lag-screw *f* may be passed into a sleeper or tie *g*.

The second portion *h* of the tie-plate has a rail-base-supporting portion *h'*, in turn provided, as above suggested, with a rail-embracing lug *i* at its free end. (Shown particularly in Figs. 1 and 2.) This second portion of the tie-plate is also provided with a base

stop-lug *m*, also oppositely disposed from the rail-embracing lug. By the term "oppositely-disposed" I mean arranged at a point on the plate directly opposite to contact the 5 opposite side of the rail-base, as shown in the drawings. This second portion is also provided with a lever-like extension *p*, perforated at a point arranged, relatively speaking, remote from the rail-base-supporting portion, 10 so as to permit the passing therethrough of a lag-screw or railway-spike *q*. In some instances this portion *p* should be extended inwardly far enough to overlap a similar inwardly-extending lever-like portion from a 15 rail-plate on the opposite rail, as shown particularly in Fig. 4, where it may be perforated at several points to permit the passing therethrough of lag-screws or railway-spikes *r* for securing the parts in operative position. This 20 latter type of plate should be disposed at convenient intervals—say from thirty to one hundred feet apart—thereby serving to preserve the absolute gage of the track, all of which will be understood and appreciated by 25 those skilled in the art.

I claim—

1. In mechanisms of the class described, a tie-plate composed of a plurality of pieces having rail-base-receiving portions provided 30 with base-embracing and stop lugs oppositely disposed, and perforated lever-like portions extending outwardly and oppositely therefrom, the perforations being arranged at points relatively remote from the base-receiving portion of the plate, substantially as described.
2. In mechanisms of the class described, a tie-plate formed of a plurality of portions, one portion having a bifurcated base-receiving 40 portion provided with base-embracing lugs at its free edges and base stop-lugs oppositely disposed and with a laterally-extending lever-like portion for securing the same to a railway-tie at a point relatively remote 45 from the base of a railway-rail, and a second portion provided with a base-receiving portion arranged between the bifurcation of the

first-named plate portion and having a rail-base-embracing lug at its free end and a base stop-lug oppositely disposed and with a laterally-extending lever-like portion perforated relatively remote from the rail-base for securing the same to the railway-tie, substantially as described. 50

3. In mechanisms of the class described, a tie-plate formed of two portions, one having a bifurcated rail-base-supporting portion provided with base-embracing lugs at its free edges and base stop-lugs oppositely disposed and with a lateral lever-like perforated extension for securing the same to the railway-tie at a point remote from the rail-base, and a second plate portion provided with a base-receiving portion arranged between the free ends of the bifurcated plate having a base-embracing lug at its free end and a base stop-lug oppositely disposed and with a laterally-extending lever-like perforated portion adapted to overlap a similar lever-like extension of a similar plate on the opposite track-rail 60 to preserve the gage of the track, substantially as described. 65

4. The combination of a rail-support, a rail, rail-holding plates having means for engaging the rail at opposite sides and also having different centers of movement, and spikes connecting the plates and the rail-support, the said rail-holding plates and the spikes being so relatively arranged that the spikes serve as the centers upon which the plates are 70 movable. 75

5. In mechanisms of the class described, the combination of a railway-rail, having a height greater than the width of its base, a tie-plate portion engaging the base of the rail 85 and provided with lever-like extensions extending outwardly and oppositely from the rail-base, and means for securing the same in position at points relatively remote from the rail-base, substantially as described. 8c
